UNITED STATES PATENT OFFICE.

CLARE H. DRAPER, OF HOPEDALE, MASSACHUSETTS, ASSIGNOR, BY MESNE ASSIGNMENTS, TO DRAPER CORPORATION, OF HOPEDALE, MASSACHUSETTS, A CORPORATION OF MAINE.

TAKE-UP MECHANISM FOR LOOMS.

Application filed December 18, 1925. Serial No. 76,205.

The present invention relates to an improvement in take-up mechanism for looms.

The take-up mechanism of a loom is ordinarily actuated as in the Northrop Patent No. 1,479,154, by mechanism which positively rotates the draw-roll, as a result of which the tension exerted by the draw-roll on the cloth being woven is a hard, unyielding tension. It has been claimed that the cloth itself in a low-roll take-up offers a yielding pull on the cloth at the fell which compensates for variations in weft sizes, with the result that the cloth exhibits a more uniform appearance than in a high-roll take-up, wherein the length of warp between the take-up roll and the fell is less. But in both cases the unyielding character of the mechanism is an objection which it is the object of the present invention to overcome by providing the mechanism with devices for exerting a yielding tension upon the cloth while it is being woven. While the invention is susceptible of embodiment in a loom provided either with a high-roll take-up or with a low roll take-up, it obviously is of larger importance in a high-roll take-up loom because of the shorter length of cloth in that loom between the take-up roll and the fell. The invention consists in the improvement herein-after described and particularly defined in the claims.

In the accompanying drawings illustrating the preferred form of the invention, Fig. 1 is a sectional elevation illustrating the take-up mechanism of a high-roll take-up loom embodying the present invention; and Figs. 2 and 3 illustrate details of construction hereinafter referred to.

The illustrated embodiment of the invention is described as follows:—The entire mechanism illustrated in this drawing with the exception of parts referred to, is identical in construction, organization and mode of operation with the mechanism illustrated and described in said patent. In order to secure the elastic or yielding operation of the take-up mechanism, the change gear 191 which constitutes a driving member is provided with a boss 192 on its side. This boss is provided with a hole 193, which receives the arcuate rod 194. This rod is rigidly secured at one end in the arm 195, provided

with the hub 196, secured to the sleeve or hollow shaft 197 by means of the set screw 198. Upon this hollow shaft 197 is integrally formed the pinion 18, which meshes with the intermediate gear 17, which meshes in turn with the gear 16, rigidly secured to the pinion 15, which meshes with the gear 14 connected with the draw-roll 13.

The arcuate rod 194 is embraced by a spring 199, which bears at one end against the boss 192 on the change gear 191, and at the other end on the collar 200, secured at the free end of the arcuate rod 194 by means of a cotter pin 201, which enters one of a series of holes 202 in the free end of the arcuate rod. By placing the cotter pin in one or the other of the holes 202, the tension of the spring 199 may be varied.

The change gear 191 is driven by means of the worm 20, as in said patent. The change gear is normally driven in the direction of the arrow 203. This rotates the change gear in the direction tending to exert a pressure upon the spring 199, which, through the arcuate rod 194, is transmitted to the arm 195 of the gear train for the draw-roll. Thus it will be seen that the pull or tension exerted upon the cloth 10 by the draw-roll 13 is a yielding, elastic tension, and not a rigid, positive tension as is exerted upon the cloth by the mechanism illustrated in said patent.

It has been found in the operation of a loom equipped with the present invention that the elastic pull exerted upon the fabric by this take-up mechanism secures a uniform interweft space between the weft threads of the cloth whereby the loom is enabled to produce a cloth with a weft of varying dimensions and of much more uniform appearance than that which is capable of being produced by a loom equipped with the mechanism of the said patent. It is apparent that a slenderer weft would naturally be beaten up into the fell a greater distance than the larger weft, and where the tension exerted upon the cloth by the draw-roll is an elastic tension, the pressure with which the wefts are beaten into the fell are made more uniform than in a case where the position of the fell was advanced toward the front of the loom a uniform distance upon each beat of the lay. This results in a more uniform spacing of

the wefts, and a superior appearance of cloth with no superior qualities of weft.

Broadly stated it may be said that the invention contemplates a take-up mechanism for looms comprising a device adapted to exert a yielding tension upon the cloth being woven and permitting backward motion of the take-up to give up cloth.

Having thus described the invention, what is claimed is:

- 10 1. In a take-up mechanism for looms, the combination of a cloth take-up roll over which the cloth passes and by which the cloth is taken up as woven, a train of gears between the take-up roll and an operating shaft of the loom for rotating the take-up roll to take up the cloth as it is woven, including a yielding driving connection between two of the gears of the train and constructed to urge the roll forward and to yield backward and also constructed to limit the relative rotation of the two gears to a fraction of one complete revolution to thereby limit the yielding movement of said roll.
- 15 2. In a take-up mechanism for looms, the combination of a cloth take-up roll over which the cloth passes and by which the cloth is taken up as woven, a train of gears between the take-up roll and an operating shaft of the loom for rotating the take-up roll to take up the cloth as it is woven, including a yielding driving connection between two of the gears of the train and constructed to urge the roll forward and to yield backward, and stops positioned to cooperate with the yielding means to limit the relative rotation of the two gears to a fraction of one

complete revolution to thereby limit the take-up and give back of the cloth being woven.

40 3. In a take-up mechanism for looms, the combination of a cloth take-up roll over which the cloth passes and by which the cloth is taken up as woven, a train of gears between the take-up roll and an operating shaft of the loom for rotating the take-up roll to take up the cloth as it is woven, including a pair of gears mounted to rotate about a common axis, a projection rigidly secured to one of said gears, and a spring connection between the projection and said other gear and arranged to urge the roll forward and to yield backward through a limited angle to thereby limit the yielding take-up and give back of the cloth being woven.

45 4. In a take-up mechanism for looms, the combination of a cloth take-up roll over which the cloth passes and by which the cloth is taken up as woven, a train of gears between the take-up roll and an operating shaft of the loom for rotating the take-up roll to take up the cloth as it is woven, including a pair of gears mounted to rotate about a common axis, a yielding connection between said gears including an arcuate rod connected to one of said gears, and a spring coiled about said rod and adapted to act against a projection on the other gears to provide a limited yielding driving connection between said gears.

50 5. In testimony whereof I have signed my name to this specification.

CLARE H. DRAPER.
